UNITED STATES PATENT OFFICE.

ARTHUR E. BENSON, OF AGRICULTURAL COLLEGE, MISSISSIPPI, ASSIGNOR
TO DRAPER COMPANY, OF HOPEDALE, MASSACHUSETTS, A CORPORA-
TION OF MAINE.

FILLING-TENSION MEANS FOR LOOM-SHUTTLES.

No. 825,886.

Specification of Letters Patent.

Patented July 17, 1906.

Application filed September 27, 1905. Serial No. 280,343.

To all whom it may concern.

Be it known that I, ARTHUR E. BENSON, a citizen of the United States, residing at Agricultural College, county of Oktibbeha and State of Mississippi, have invented an Improvement in Filling-Tension Means for Loom-Shuttles, of which the following description, in connection with the accompanying drawings, is a specification, like figures on the drawings representing like parts.

This invention has for its object the production of novel means for imparting additional tension to the filling in a loom-shuttle at or about the instant the shuttle is nearly boxed, to thereby render the filling taut between the shuttle and the edge of the cloth.

If the filling is taut, the detecting action of the filling-fork is performed in a much better manner than if the filling is slack, and slackness also permits the filling to twist or kink. When looms are provided with automatic filling-replenishing mechanism and with means to part the old filling end between the cloth and the shuttle, (upon filling replenishment,) it is of great importance to have the filling taut between the cloth and the boxed shuttle—that is, immediately after the shuttle is boxed for replenishment the filling is clamped first near the shuttle and thereafter it is parted between the clamp and the shuttle, and while still clamped the parted filling end is brought into the range of a temple thread-cutter to be parted adjacent the edge of the cloth. Consequently if the filling is slack it may twist or kink out of reach of the clamping and parting devices, so that they cannot operate properly and the filling end will break, the broken end often flying back to be woven into the cloth, making an imperfection therein. By my present invention the increase in the tension on the filling as the shuttle-boxes prevents such objectionable occurrences.

A loom provided with parting and clamping means such as hereinbefore referred to is shown in United States Patent to Draper, No. 683,423, dated September 24, 1901, to which reference may be had.

In accordance with my present invention the tension-controlling means is located on the shuttle and is automatically operated as the shuttle is boxed.

The various novel features of my inven-

tion will be fully described in the subjoined specification and particularly pointed out in 55 the following claims.

Figure 1 is a top plan view of the shuttle-box of a loom with a shuttle therein embodying one form of my invention, the shuttle and the front box-wall being partly broken 60 out to show the operation. Fig. 2 is an enlarged top plan view of the delivery end of a loom-shuttle with one form of my invention applied thereto; and Fig. 3 is a transverse section on the line 3 3, Fig. 2, looking toward 65 the right.

I have shown in Fig. 1 a shuttle-box at the right-hand side of a loom, the box comprising the fixed front wall 1 and cover or guard-plate 2, mounted on the lay 3, the binder 4 70 and picker 5 being also shown. This construction is suitable for either a plain loom or one provided with automatic filling-replenishing mechanism of the type shown in United States Patent to Northrup, No. 75 529,940, and I have shown the shuttle 6 as of the automatically self-threading type, open at 7 to receive the filling-carrier 8 and having thread-delivering means, shown herein as a self-threading device 9 of any suitable construction. This device is adjacent one end of 80 the opening 7, and in the opposite end of such opening the shuttle is shown in Fig. 1 as provided with holding-jaws 10 for the butt of the filling-carrier, all of substantially well-known construction.

While I have shown a self-threading shuttle herein, my invention is not restricted to use therewith, as it can be used with facility in an ordinary loom-shuttle. The shuttle 90 wood is cut away at 11 in front of the thread-delivering means 9, the filling 12 passing therethrough from the tip of the filling-carrier in usual manner to be delivered.

In accordance with my present invention 95 I mount a spiral tension member 13 in the cut-away part 12 transverse to the path of the filling and just below it, so that the filling will draw between two adjacent coils as it is delivered from the shuttle. One end of the 100 spiral is attached to the shuttle-body, as at 14, Figs. 2 and 3, and its opposite end is secured to the inner end of the compressor 15, (shown as a short pin slidably mounted in a hole 16 in the shuttle,) said hole being counterbored at its outer end to receive the head 105

17 of the compressor, the outer face of the head being rounded, Figs. 2 and 3. The expansibility of the spiral normally maintains the coils thereof far enough apart to let the filling draw through as freely as desired, and it also maintains the compressor in the position shown in Figs. 2 and 3, with its rounded head projecting slightly beyond the side of the shuttle. By pressing the compressor inward the spiral 13 will be compressed and its coils thereby moved toward each other to increase the tension on the filling and act as a drag thereon. This operation of the compressor is effected herein by engagement of the head 17 thereof with the inner face of the fixed wall of the shuttle-box. When the thread-delivering end of the shuttle is ahead, as when entering the right-hand shuttle-box, the instant increase of the tension as soon as the compressor-head engages the inner end of the box-wall 1 might tend to break the filling, and I therefore make a longitudinal depression 18 in the wall from its inner end to the point at which the increase of tension may safely be effected. This, as shown in Fig. 1, is when the shuttle is approaching the end of its flight, and as soon as the head of the compressor reaches the outer end of the depression 18 it rides up on the face of the wall and is thereby forced inward, so that the member 13 increases the tension. As a result, the filling is drawn properly taut between the shuttle and the edge of the cloth, as in Fig. 1. When the shuttle is boxed at the opposite side of the loom, the delivery end is near the mouth of the box, and as the compressor-head will not engage the front wall of the box until the end of the shuttle flight approaches no depression or other change in such wall is usually necessary. For that reason I have not shown the opposite shuttle-box in the drawings with the filling taut, as at 12^x, Fig. 1. The same is in the most efficient condition for the coöperation of a thread clamping and

parting device, such as previously referred to, 45 if the loom be so equipped or for engagement by the filling-fork in an ordinary loom.

Having fully described my invention, what I claim as new, and desire to secure by Letters Patent, is—

1. The combination, in an automatically self-threading loom-shuttle adapted to receive a supply of filling, of a tension device carried by the shuttle and including a transversely-arranged spiral, the filling passing 55 between adjacent coils thereof, and a compressor to move the coils toward each other and thereby increase the tension on the filling.

2. The combination, in an automatically self-threading loom-shuttle adapted to receive a supply of filling, of a spiral tension member arranged transversely to the path of the filling, and a compressor connected with the said member and having a head projecting beyond the side of the shuttle, inward 60 pressure on the head acting to compress the spiral member and thereby increase the tension on the filling.

3. The combination, in a loom-shuttle having guiding and delivering means for the filling, of a tension spiral carried by the shuttle adjacent said means and adapted to receive the filling between adjacent coils, and a compressor movably mounted in the shuttle and connected at its inner end with the spiral, the 70 outer end of the compressor normally projecting beyond the shuttle side, inward movement of the compressor pressing the coils of the spiral toward each other, to increase the tension on the filling.

In testimony whereof I have signed my name to this specification in the presence of two subscribing witnesses.

ARTHUR E. BENSON.
